DOOR OPERATED SAFETY DEVICE FOR
OIL-BURNING FURNACES

Frank B. Scanlon, Beachwood, and George A. Isaac, Audubon, N. J.

Application February 12, 1948, Serial No. 7,986

5. Claims. (Cl. 158—42.1)

1

This invention relates to new and useful improvements in oil burning furnaces and more particularly, this invention relates to the subject matter disclosed in co-pending application Serial No. 682,409, filed July 9, 1946, now Patent No. 2,469,082, issued May 3, 1949.

The primary object of the present invention is to provide a device for simultaneously closing the fuel supply to an oil burning furnace and opening the igniting mechanism circuit of the oil burning furnace when the combustion chamber door of the furnace is opened by an internal, unsafe explosion in the combustion chamber.

Another important object of the present invention is to provide a safety device for oil burning furnaces including a novel and improved valve for closing the fuel supply to the furnace should the combustion chamber door thereof be opened due to inefficient operation of the furnace.

A further object of the present invention is to provide a safety attachment for oil burners including a valve for controlling the fuel supply to a furnace, a switch for the igniting mechanism circuit of the furnace and novel and improved means for actuating the valve and the switch to prevent continued operation of the furnace should the combustion chamber door of the latter be opened due to an internal explosion within the furnace combustion chamber.

A still further aim of the present invention is to provide a safety device of the aforementioned character that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a longitudinal vertical sectional view of the present invention, and showing the valve holding bar disengaged from the valve;

Figure 2 is a perspective view of the lower portion of the present safety device, and with parts of the burner fuel line broken away;

Figure 3 is a diagrammatic view showing the present invention applied to the combustion chamber door of the oil burner;

Figure 4 is an enlarged horizontal sectional view taken substantially on the plane of section line 4—4 of Figure 3;

2

Figure 5 is a transverse horizontal sectional view taken substantially on the plane of section line 5—5 of Figure 1; and

Figure 6 is a fragmentary longitudinal vertical sectional view taken substantially on the plane of section line 6—6 of Figure 1.

Referring now to the drawings in detail, wherein for the purpose of illustration, there is disclosed a preferred embodiment of the present invention, the numeral 10 represents a substantially cylindrical chamber which is divided into an upper fuel compartment 12 and lower fuel compartment 14 by an integral partition 16 the central portion of which is depressed to provide a substantially conical valve seat 18 having a plurality of fluid passages or apertures 20.

Extending upwardly from the chamber 10, is a raised central, annular portion 22 that frictionally engages the lower open end 24 of a substantially cylindrical housing 26 having a rounded, closed upper end 28. The lower end 24 of the housing 26 supports a plurality of circumferentially spaced screws 30 that receivably engage internally threaded apertures 32 provided in the raised central portion 22 to removably secure the housing 26 to the chamber 10.

Integrally formed with and projecting upwardly from the center of the raised central portion 22, is an externally threaded sleeve 34 that receivably engages an adjustable collar 36 having a central guide opening 38 that aligns the opening 40 formed in the raised central portion 22. A sealing gasket 42 is interposed between the collar 36 and sleeve 34. Integrally formed with the upper rounded end 28 of the housing 26, is a guide sleeve 44, having an opening 46 that aligns the opening 38 in the guide collar 36.

Slidably positioned in the openings 38, 40 and 46 is a substantially vertical, cylindrical valve 48 having a conical end portion 50 that is adapted to frictionally engage the valve seat 18. Mounted on the valve 48 in any suitable manner, is a laterally extending switch actuating rod 52 that is slidably positioned in a substantially channel shaped switch compartment or recess 54 integrally formed with the housing 26. Loosely embracing the valve 48, is a coil spring 56 which is biased between the switch actuating rod 52 and the inner face of the rounded upper end 28 to urge the conical end portion 50 of the valve 48 into the valve seat 18 to close the apertures 20.

Suitably fixed in compartment 54 is a conventional precision switch mechanism 58 having a resilient actuating arm 60 and a spring urged switch control plunger 62 that is normally urged to a circuit closed position to complete the cir-

cuit between the pair of conductive wires 64 and 66 that are connected to the switch mechanism 58 and the electrical igniting mechanism circuit for an oil burning furnace 68.

Communicating with the upper fuel compartment 12, is an inlet nipple 70 that is operatively connected to a suitable source of fuel by a conduit 72, and extending outwardly from the lower fuel compartment 14, is an outlet nipple 74 that is connected to the delivery line 76 for the furnace 68.

In practical use of the present invention, the valve 48 is gripped by its knurled upper end 78 and raised against action of the spring 48, so that the transverse aperture or opening 80 therein will align with an opening 82 in the sleeve 44. One end of a valve holding bar 84 is frictionally positioned in the openings 80 and 82 to retain the valve 48 in an open position, and the switch 58 in a circuit closed position, as shown best in Figure 1 of the drawings.

Suitably fixed on the frame 86 of a hinged combustion chamber door 87 of the furnace 68, is the inner end of a pair of spaced parallel arms 88 having a plurality of longitudinally spaced openings 90 that adjustably support a pivot pin 92. The pin 92 selectively engages one of a plurality of longitudinally spaced apertures 94 formed in a connecting link 96 one end of which is pivoted to the bifurcated end 98 of a socket 100 that threadingly engages the free end 102 of the valve holding bar 84.

Should the door 87 be opened from an internal explosion within the oil burning chamber 68, the same will contact the upper portion of link 96 to swing the link 96 and the bar 84 will be pulled toward the furnace 68 to disengage the bar 84 from the sleeve 44 and valve 48 thus causing the valve 48 to slide downwardly in the housing 26 to close the apertures 20. As the valve 48 slides downwardly, the switch actuating rod 52 will frictionally engage the arm 60 to force the plunger 62 inwardly in the switch mechanism 58 to open the igniting mechanism circuit for the furnace 68.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A safety device for oil burning furnaces comprising a cut-off valve for the fuel line of a burner, a switch for controlling the igniting mechanism of a furnace, a laterally projecting arm carried by said valve for actuating said switch, means urging said valve to closed position, and means normally holding the valve in open position, said last-mentioned means including a slidable holding rod adapted to engage said valve and a rockable link for actuating said rod to release the valve, said link adapted to be disposed in the path of a furnace door.

2. In an oil burning furnace having a door and an ignition mechanism switch, a safety device

comprising a housing having a recess therein for said switch, a fuel chamber in said housing through which fuel passes to the fuel line of the furnace, said chamber having an entrance port, a valve slidably carried by said housing for closing said port, a laterally projecting arm carried by said valve and disposed within the housing for operating the switch, means urging the valve to a position for closing the port, means normally holding the valve out of its closed position and the arm from its switch operating position, and means responsive to an opening of the door for disengaging said last-mentioned means with said valve.

3. In combination with an oil burner having a door and an igniting mechanism circuit, of a safety device comprising a hollow body forming a fuel chamber and having a partition therein dividing the chamber into upper and lower compartments, an inlet nipple carried by the body and leading to the upper compartment, an outlet nipple carried by the body and leading from the lower compartment, said outlet port adapted to be connected to the fuel line of the furnace, an apertured valve seat provided in said partition whereby fuel in said upper compartment passes into said lower compartment, a housing detachably secured to said body and having a recess, a switch controlling the igniting mechanism circuit mounted in said recess, a cylindrical valve member slidably carried by said housing and having a tapered lower end for positioning in said valve seat to restrict a flow of fuel from said upper compartment into said lower compartment, a spring embracing the valve member and urging the same to its closed position, an arm carried by and projecting laterally from said valve member for operating the switch, means normally holding the valve member in its open position, and means responsive to an explosion in the furnace for urging said last-mentioned means to a position for releasing the valve member, said arm actuating said switch to a circuit-closing position simultaneously with the movement of said valve member to its closed position.

4. A safety device for oil burning furnaces, said device comprising a casing having a substantially horizontal partition therein for dividing the casing into upper and lower compartments, said upper compartment having an inlet and said lower compartment having an outlet, said partition including an opening for the passage of fuel from the upper compartment into the lower compartment, a housing rising from the casing, an elongated valve slidably carried by the housing and having an end portion for closing the opening in the partition, a switch for the ignition mechanism of a furnace mounted within the housing, an arm supported solely by the valve and positioned within the housing for actuating the switch upon movement of the valve to its closed position, means yieldingly urging the valve to its closed position, and means disposed exteriorly of the housing for retaining the valve away from the opening in the partition and the arm from its switch operating position.

5. A safety device for oil burning furnaces, said device comprising a casing having a substantially horizontal partition therein for dividing the casing into an upper fuel compartment and a lower fuel compartment, a valve seat in the partition, said valve seat having openings for the passage of fuel from the upper compartment into the lower compartment, said upper compartment having an inlet and said lower compartment

ment having an outlet, a housing supported on and rising from the casing, a hollow switch compartment projecting laterally from the housing, a valve slidably carried by the housing for entering the valve seat to close the openings in the valve seat, a switch in said switch compartment, an arm projecting laterally from and movable with said valve for actuating the switch upon movement of the valve to its closed position, means for urging the valve toward the valve seat, and means for retaining the valve away from the valve seat.

FRANK B. SCANLON.
